CLAIM

The ornamental design for a packaging, as shown and described.

DESCRIPTION

FIG. 1 is a top, front, right side perspective view of a packaging showing my new design;

FIG. 2 is a bottom, rear, left side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a top, front, right side perspective view of the packaging in an environment in which it may be used; and, FIG. 10 is a bottom, rear, left side perspective view thereof. The dashed broken lines in the figures show portions of the packaging and environment that form no part of the claimed design.

The dot-dashed broken lines in the figures, and the areas within the dot-dashed broken lines show portions of the packaging that form no part of the claimed design.
